UNITED STATES PATENT OFFICE.

ANDREW GEORGE SCHWARTZ, OF CHICAGO, ILLINOIS.

BANK FORTIFICATION.

Application filed October 24, 1925. Serial No. 64,491.

This invention relates to bank fortifications and has for its object the provision of a fortified tower which is so positioned in and associated with the usual bank cage as to command a maximum amount of floor space of the bank. This invention is not limited for use in banks but also may be used to protect any business transactions which would normally be exposed to banditry.

It is also an important object of this invention to provide a fortification which affords a maximum of defense for the guard or person retreating therein and which also affords a maximum amount of offensive means whereby said guard or person may rout any unlawful assailants.

Other and further important objects of this invention will be apparent from the disclosures in the specification and the accompanying drawings.

The invention (in a preferred form) is illustrated in the drawings and hereinafter more fully discussed.

On the drawings:

Figure 1 is a fragmentary plan view showing the general arrangement of the device embodying this invention, with a bank.

Figure 2 is a fragmentary front elevational view of the same.

Figure 3 is a fragmentary rear elevational view of the same.

Figure 4 is a fragmentary vertical section with parts omitted, taken at the line IV—IV of Figure 1.

Figure 5 is an enlarged detail fragmentary vertical sectional view with parts omitted, showing the releasable catch for holding the tower window partly open.

Figure 6 is a reduced fragmentary detail horizontal section taken at the line VI—VI of Figure 5.

Figure 7 is an enlarged horizontal section with parts omitted taken at the line VII—VII of Figure 4.

Figure 8 is an enlarged fragmentary section with parts omitted taken at the line VIII—VIII of Figure 7.

Figure 9 is an enlarged horizontal section with parts omitted taken at the line IX—IX of Figure 4.

Figure 10 is an enlarged fragmentary detail vertical section taken at the line X—X of Figure 9.

Figure 11 is an enlarged detail fragmentary vertical section taken at the line XI—XI of Figure 9.

Figure 12 is a fragmentary vertical section of the tower, showing a modification.

As shown on the drawings:

This invention comprises a fortified tower 1 which is situated midway out of a bank cage 2, or the like, which it is desirous of protection. Surrounding the outer half of a tower 1 and spaced therefrom a suitable distance is a semi-circular railing 3 which extends to the cage 2 on either side of said tower. An entrance to the tower 1, as will be later described, is in the rear of the cage 2 and is protected from lateral fire by rearwardly extending panels 4 and 5 on either side of said tower. The tower 1 is of steel and is of a thickness which is sufficient to resist or prevent penetration of revolver or rifle bullets therethrough. The tower being round, it is more capable of turning aside any bullets which may be directed against the sides thereof.

An arcuate observation opening 6 is cut out of the front of the tower 1 and is protected by a series of vertical bars 7 arranged across said opening on the exterior thereof and secured to said tower. An arcuate closure 8 of slightly larger area than the opening 6 and concentric with the tower is vertically slidable in guides 9 mounted in the interior of the tower along the vertical edges of said closure. The closure 8 is provided with a horizontal inwardly extending flange 9^a at the lower edge thereof to which is secured a pair of horizontally spaced downwardly extending guide rods 10 slidable in brackets 11 secured to the interior of the tower. Surrounding the rods 10 and compressed between the respective brackets 11 and flange 9^a are compression springs 12. A pivoted hook 13 is mounted near the upper inner edge of the closure 8 for engagement with a bolt 14 secured to the tower for holding said closure in an upwardly closed position. A pair of weights 15 connected to respective cords 16 are mounted over pulleys 17 rotatably secured to the inner side of the tower and are connected to the opposite sides of the closure 8 for assisting the springs 12 in tending to close said closure.

By referring to Figure 2, it will be seen that the tower is provided with a pair of lower vertical slots in which are mounted in the exterior thereof vertically extending diverging nozzles 18 which with said slots constitute loop-holes. The upper portion of the tower is provided with a series

of horizontal arcuate slots in which are mounted horizontally extending diverging nozzles 19 which with said slots form loop-holes. Within the tower are vertically slideable rods 20. The rods 20 are adapted to slide in upper and lower brackets 21 and 22 respectively and are normally held in upward position by springs 23 surrounding said rods. The springs 23 are normally compressed between inwardly extending handles 24 secured to said rods and the brackets 22. The handles 24 normally abut the upper brackets 21 and act as stops to limit the vertical movement of the rods 20. When the rods 20 are in normal upward position, they are adapted to close the loop-holes formed by the vertical apertures in which are mounted the nozzles 18. When it is desired to open the loop-hole to fire out of the nozzles 18 it is merely necessary to press the handles 24 downwardly. Upon releasing the handles 24, their respective apertures will immediately be closed by action of the springs 23.

25 A suitable arcuate writing desk 25 is provided within the tower which may be used as a step or platform from which to fire out of the loop-holes comprising the nozzles 19 and slots therefor.

30 A bell crank lever 26 pivotally mounted within the forward side of the tower is provided with a hook 27 on the upper arm thereof which is normally held in vertical position against a stop 28 by means of a spring 29, the latter being secured with one end to said arm and the other end to the side of the tower. The other arm of the lever 26 is substantially horizontal and is connected through a cord 30 to an arcuate plate 31. The flange 9^a of the closure 8 is provided with a notch 32 which is adapted to engage with the hook 27 when the closure is in downwardly open position for the locking of the latter in said position. The plate 31 is vertically slideable in guides 32 secured to the inner side of the tower. The plate 31 is normally held in upward position in the guides 31 against suitable stops therein by means of a pair of springs 33 compressed beneath the opposite ends of said plate and the bottom of the tower. Mounted within a suitable recess in the guide 9 is a pivoted bell crank lever 34 which is provided at its upper end with a locking lug 35.

55 The lever 34 is provided with a suitable spring for normally holding the lug 35 to the left as shown in Figure 5 for engagement in any one of a vertically arranged series of notches 36 in the edge of the closure 8. The lever 34 is provided with a substantially horizontal arm which is connected through a cord 37 to the plate 31. If the closure 8 is open as far as possible, it will normally be held open by the hook 27 of the bell crank lever 26. If it is only desired to

have the closure 8 held partly open, it may be held in such position by the lug 35 of the bell crank lever 34. Thus in either fully open or partly open position the closure 8 may be released by stepping on the plate 31 or in a manner which will be described hereinafter.

75 A conical steel roof 38 is secured to the top of the tower at the inner edges thereof through flanges 39.

The rear side of the tower as shown in Figure 3 is provided with a pair of vertical outwardly swung doors 40 and 41. The doors 40 and 41 are normally held in inwardly closed position by powerful springs 42. Each of the doors 40 and 41 is provided with a loop-hole comprising a vertical slot and vertically extending diverging nozzle 42^a therein similar to the nozzles 18. The latter nozzles and slots associated therewith are provided with automatic closures similar to the rods 20 and parts associated therewith. Each of the doors 40 and 41 is also provided with a loop-hole comprising a horizontal upper aperture and horizontally extending diverging nozzle 43 similar to the nozzles 19. The nozzles 19 and 43 are arranged with their upper and lower edges in substantially the same horizontal plane. A cylindrical ring 44 is mounted within the tower above the closure 8 and extends to the inner periphery of said tower. The ring 44 is adapted to rotate on rollers 45 secured to and spaced about the inner periphery of the tower and may be rotated about said rollers 100 for selectively registering a horizontal slot 46 in said ring with any one of the loop-holes including the nozzles 19 or 43. A bracket 47 is secured to the ring 44 adjacent the lower edge of the slot 46 for supporting a shooting iron thereon. A suitable handle 48 is secured to the ring 44 for facilitating the rotation of said ring for selectively positioning the slot 46. The ring 44 is provided with a pair of hinged sections 49 and 50 which normally extend across the opening between the outer edges of the doors 40 and 41 and which may be folded to the left to the dotted line position shown in Figure 7 so that when the doors are in open 115 position, the ring 44 will not obstruct the passage therethrough. In normal position, the closure 8 is pressed downwardly in either partly open position or fully open position and held by either the lever 34 or the lever 120 26, as the case may be.

125 The doors 40 and 41 are normally in openly swung position as indicated in dotted lines of Figure 9. The doors 40 and 41 are held in open position by means of stops or trips 51 and 52. The stops 51 and 52 each consists essentially of a vertically slideable lug member mounted in a base 53 and normally held in upward position for engagement with the lower edge of its respective door by 130

means of a spring 54 held within said base beneath the bottom of said lug by a threaded nut 55 screwed in said base. The nut 55 is apertured to receive therethrough a tension transmitting means such as cord 56 which is secured to the bottom of the lug and which passes over a pulley 57 mounted within said base. Each of the cords 56 from the lugs 51 and 52 passes over a horizontal roller 58 and enters the tower at the rear thereof through a suitable aperture and is connected to a releasing device which will now be described.

The releasing device is mounted in the center of the tower and consists of a plunger 59 having a large flat head. The plunger 59 is vertically slidable in a hollow base 60 which is provided with diametrically positioned vertical slots 61. The plunger 59 is normally held in upward position within the base 60 by a spring 62 which is supported in said base by a nut 63 threaded in the bottom of said base. A diametrical pin 64 extends through the lower portion of the plunger 59 through the slots 61 and limits the upward vertical movement of said plunger by the spring 62. Secured on each end of the pin 64 is a bracket 65 and 66 respectively which pivotally support the upper ends of links 67 and 68. The lower ends of each of the links 67 and 68 are provided with a suitable cam surface so that when the plunger 59 is forced downwardly, said lower ends will cam outwardly causing the links to assume a dotted line position shown in Figure 11. Referring now to Figure 9, the cords 56 from the stops 51 and 52 are joined together within the tower and connected to a single cord 69 which extends through a suitable horizontal aperture through the bottom of the base 60 and is secured to the lower end of the link 68 on the further side thereof. A cord 70 is secured beneath the plate 31, passes over a pulley 71, horizontally mounted in a bracket 72 secured to the bottom of the tower and thence passes through the horizontal aperture through the bottom of the base 60 and is secured to the lower end of the link 67. Thus when the plunger 59 is forced downwardly, the lower ends of the links 67 and 68 will move outwardly, pulling the cords 70 and 69 respectively for actuating the stops 51 and 52 to automatically close the doors 40 and 41 and to actuate the plate 31 downwardly for tripping either the lever 26 or the lever 34 to automatically close the closure 8. A megaphone or alarm signal 70a is provided on the tower.

In Figure 12 is shown a modification wherein the tower in order to facilitate and simplify construction is made of two sections, an upper section 71 and lower section 72 which are separated or joined by a ring 73 which is provided with an inner flange

74 at its upper and lower inner edges 74 and 75 respectively. The ring 73 is provided with a series of loop-holes and nozzles therefor 76 spaced about the periphery of said ring. In this modification the inner rotatable ring 77 is similar to the inner ring 44 in the previous embodiment with the exception that it is of slightly smaller diameter, being inside of the flanges 74 and 75 and it is not provided with the hinged sections such as the sections 49 and 50 because in this modification the doors 40 and 41 would not come up as high as in the previous modification.

Operation.—In case of attack, a guard duly stationed in the tower or any one on duty about the tower either as a guard or in any capacity may retreat into the tower, press the plunger 59 downwardly by stepping on the head thereof for automatically closing the doors 40 and 41 and the front closure 8. The sections 49 and 50 may be folded into operative position and the ring 44 rotated to open any of the loop-holes leading to the nozzles 19 or 43 to permit shots to be fired through said loop-holes at the attacking force. The catch 13 may be thrown over the bolt 14 to insure against any one forcing the closure 8 downwardly from without. The desk 25 may be used as a platform from which to fire out of the nozzles 19. A person in the tower may fire out of the loop-holes and nozzles 18 or 42a as previously described by grasping the handles 24 and forcing the rods 20 downwardly to uncover the inner ends of said loop-holes. As soon as the handles 24 are let go, the loop-holes will be automatically closed thus preventing any one firing back into the same from without the tower. The ring 44 will prevent any one from shooting a man in the tower through any of the loop-holes and nozzles therefor 19 or 43 while said man is looking out of another one of said loop-holes. The tower 1 may be advantageously used for many purposes such as an outpost or guard house for a military post or a guard house for prisons or the like, without departing from the spirit of this invention.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A device of the character described comprising a bullet proof tower having an entrance opening and an observation opening therein, closures for said openings normally in open position, and means for releasing said closures instantaneously.

2. A device of the character described comprising a bullet proof tower having an

opening therein, a slidable closure therefor, means acting to close said closure, a releasable catch for holding said closure open against said means, and a substantially centrally positioned mechanism in said tower for releasing said catch.

3. A device of the character described comprising a bullet proof tower having a plurality of loop holes therein arranged about the periphery thereof, and unitary means for selectively closing all but one of said loop holes.

4. A device of the character described comprising a cylindrical bullet proof tower having a plurality of loop holes therein arranged about the periphery of said tower, a rotatable cylindrical member mounted within said tower adjacent said loop holes, said cylindrical member having an aperture therein adapted to selectively register with any one of said loop holes.

5. A device of the character described comprising a bullet proof tower having a plurality of loop holes arranged about the periphery of said tower, outwardly extending diverging nozzles on said tower communicating with said loop holes, a shooting iron support, a movable mount therefor for selectively moving said support adjacent any one of said loop holes.

6. A device of the character described comprising a bullet proof tower having an entrance opening therein for retreat there-through, swingable means for closing said opening, closing means for said swingable means, releasable catch means for holding said swingable means open against the action of said closing means, and a conveniently positioned mechanism in said tower for releasing said catch means.

7. A device of the character described comprising a bullet proof tower, a plurality of loop holes arranged about the periphery thereof, and a movable member adapted to be selectively positioned in said tower for selectively closing simultaneously all but one of said loop holes.

8. A device of the character described comprising a bullet proof tower, a plurality of

loop holes therein arranged about the periphery thereof, rollers mounted upon the inner periphery of said tower, a rotatable ring within said tower mounted on said rollers and having an aperture therein adapted to register with any one of said loop holes.

9. A device of the character described comprising a bullet proof tower having an entrance opening and observation opening therein, automatic closures for said openings normally held in open position, means within said tower for releasing said closures, said tower having a plurality of loop holes therein arranged about the periphery thereof, selective means for automatically closing all but one of said loop holes, said tower having a plurality of additional loop holes therein, closures for the inner end of said additional loop holes, spring means acting to normally hold said latter closures in closed position and means for manually withdrawing said latter closures against the action of said spring means.

10. In a tower having an entrance opening, hinged closures for said opening, resilient means associated with said closures to normally urge said closures over said opening, stops for selectively maintaining said closures removed from said opening, and controlling means within said tower, operatively connected to said stops.

11. In a tower having an entrance opening, hinged closures for said opening, resilient means associated with said closures to normally urge said closures over said opening, stops for selectively maintaining said closures removed from said opening, controlling means within said tower, operatively connected to said stops, said controlling means comprising a reciprocal plunger, pivotal arms associated with said plunger, tension transmitting means connecting said stops and arms, and spring means for normally maintaining said stops and plunger in an operative position.

In testimony whereof I have hereunto subscribed my name.

ANDREW GEORGE SCHWARTZ.
